UNITED STATES PATENT OFFICE.

MARIUS H. HANSEN, OF CHICAGO, ILLINOIS.

DESIGN FOR A SCALE-BEAM.

SPECIFICATION forming part of Design No. 28,266, dated February 8, 1898.

Application filed December 27, 1897. Serial No. 663,774. Term of patent 14 years.

To all whom it may concern:

Be it known that I, MARIUS H. HANSEN, a citizen of the United States, residing at Chicago, in the county of Cook and State of Illinois, have invented and produced a new and original Design for a Scale-Beam, of which the following is a specification, reference being had to the accompanying drawings, which are made a part thereof, and in which—

10 Figure 1 is a perspective view of a scale-beam embodying the new design. Fig. 2 is an elevation thereof.

As shown in the drawings, one end of the beam resembles in shape the letter **T**, while 15 the other end resembles the letter **Y**. The stem A of the **T**-shaped portion is of **V** shape on one side and on the opposite side has a longitudinal depression *a* of curved cross-sectional shape. The extremities of the cross- 20 arm A' of the **T**-shaped portion join the extremities of the diverging branches B of the **Y**-shaped portion. The stem B' of the **Y**-shaped portion terminates in a laterally-projecting arm C. The stem A of the **T**-shaped 25 portion terminates in a laterally-projecting arm D, from which projects laterally a stud *d*. The arms C and D project from the same side of the beam, and from its opposite side

projects a short arm E, which is disposed at the juncture of the stem and cross-arm of the 30 **T**-shaped portion.

The essential and leading feature of this design is the general shape of the beam, which comprises the substantially **T**-shaped portion and the substantially **Y**-shaped portion, with 35 the extremities of the cross-arm of the **T**-shaped portion united to the extremities of the branching arms of the **Y**-shaped portion.

Minor features of the design are the arm proceeding laterally from the stem of the **Y**-shaped portion, the described cross-sectional shape of the stem of the **T**-shaped portion, the arm proceeding laterally from the extremity of the stem of the **T**-shaped portion, and the arm proceeding laterally from the 45 juncture of the stem and cross-arm of the **T**-shaped portion.

Having thus described my invention, what I claim as new therein, and desire to secure by Letters Patent, is—

The design for a scale-beam substantially as herein shown and described.

MARIUS H. HANSEN.
